HOLDER FOR STICK MATERIALS

Charles N. Coryell, Mamaroneck, N. Y.

Application November 21, 1934, Serial No. 754,061

10 Claims. (CL. 206—56)

The invention relates to containers, and more particularly to holders for dispensing stick material and the like.

According to one form of the invention, the container may comprise an outer holder tube in which is disposed an inner operating tube. One of these tubes may have a longitudinal straight slot and the other tube may have a helical slot. Disposed within the operating tube is a carrier member for carrying the stick material, said carrier member having a part disposed in said slots. The operating tube may have a lower annular operating ring, rotation of which causes the carrier member to advance or retract. The holder tube may have a cover hinged thereto and having snap engagement therewith. The operating tube may have a cam surface engaging a part on the cover so that the initial operating movement to advance the stick material causes the cover to snap open automatically.

In another form of the invention, provision may be made for a limited longitudinal movement of the operating tube within the holder tube so that, before rotating the annular hand operating ring for advancing the lip stick, the ring may be given a short longitudinal movement to cause the cover to snap open.

In still another form which the invention may take, the operating tube may be provided with a thumb piece projecting through a slot in the holder tube. This slot may have a short longitudinal offset so that the finger piece may be given a short initial longitudinal movement to cause the cover to snap open after which the finger piece may be moved in the circular portion of the slot in the holder tube causing the stick material to advance.

The invention also consists in certain new and original features of construction and combinations of parts hereinafter set forth and claimed.

Although the novel features which are believed to be characteristic of this invention will be particularly pointed out in the claims appended hereunto, the invention itself, as to its objects and advantages, and the manner in which it may be carried out, may be better understood by referring to the following description taken in connection with the accompanying drawings forming a part thereof, in which

Fig. 1 is a longitudinal section of one form of the invention;

Fig. 2 is a perspective of this form;

Fig. 3 is a detail on the line 3—3 of Fig. 1;

Figs. 4 and 5 are sections on the lines 4—4 and 5—5, respectively, of Fig. 1;

Fig. 6 illustrates the operating tube;
Fig. 7 illustrates a part of the holder tube;
Fig. 8 is a vertical section of another form of the invention;

Fig. 9 is a perspective view thereof;
Fig. 10 illustrates the operating tube of this form of the invention;

Fig. 11 is a vertical section illustrating still another form which the invention may embody;
Fig. 12 is a perspective of such form;

Fig. 13 is another longitudinal section of this form;

Fig. 14 is a section on the line 14—14 of Fig. 11;
Fig. 15 is a section on the line 15—15 of Fig. 13;
Fig. 16 illustrates the operating tube; and
Fig. 17 illustrates the holder tube.

In the following description and in the claims, various details will be identified by specific names for convenience, but they are intended to be as generic in their application as the art will permit. 20
Like reference characters denote like parts in the several figures of the drawings.

In the drawings accompanying and forming part of this specification, certain specific disclosure of the invention is made for purposes of explanation, but it will be understood that the details may be modified in various respects without departure from the broad aspect of the invention. 25

Referring now to the drawings, and more particularly to the first species shown in Figs. 1 to 7, this container comprises, in general, a holder tube 1, operating tube 2, carrier 3 holding stick material 4 and a hinged cover 5. The holder tube 1 may comprise a body 6 having relatively thick walls and made of moulded material, such as bakelite. The body 6 has an inner helical groove 8 and a reduced upper end in which tightly seats a sleeve 7 which is preferably made of metal having a color contrasting with the color of the body 6 for artistic effect. 30

The cap 5 is provided with a hinge connection 9 of any well known construction for connection to the sleeve 7. The cap has a substantially flat top wall and an annular depending side wall, part of which is indented at 10 to form a catch which engages with lug 11 on the sleeve 7. The cap is also provided with a depending projection 111 for a purpose hereinafter described more in detail. When the cap 5 is closed manually, the elasticity of the metal causes the parts 10 and 11 to give, causing the cap to close with a snap action, as will be understood by those skilled in the art. 45

The operating tube 2 in the form shown is made from flat stock which is rolled to form a tube. This tube has a straight slot 12, a lower flange 13, 50

a tongue 15 and a cam surface 16. Forming part of the operating tube is a lower plate 14 having its edge rolled or spun over the flange 13, as indicated in Fig. 1, to close the bottom of the container and to provide a knurled hand engaging ring for operating the lip stick.

The carrier 3 is provided with a struck out portion 17 riding in slots 8 and 12 and also has a plurality of nibs 18 for limiting the position of the stick material 4 seating in the carrier 3.

The parts are assembled as indicated in Fig. 1 which illustrates the closed position of the container with the lip stick fully retracted, the projection 17 engaging the bottom of slot 12. After assembly, the tongue 15 is struck over to engage the upper edge of body 6 so that the body 6 is held between tongue 15 and the hand operating member 14. To use the container, the operating ring 14 is turned, the initial movement thereof causing the cam surface 16 to ride under the projection 111, this forcing the catch members 10 and 11 apart and putting these parts of the container under an elastic stress.

As the hand member 14 is turned still further, the end of the depressed portion 10 rides over the top of lug 11, causing these parts which have been subjected to elastic strain to suddenly return to normal position, this giving the cover 5 an abrupt flip causing it to swing back to the position shown in Fig. 2. Further movement of the operating member 14 causes the stick material 4 to advance to the desired extent. After use, the operating member 14 is rotated in the opposite direction, causing the carrier to retract to the position shown in Fig. 1, after which the cover 5 is closed manually by the fingers.

Referring now to the second form illustrated in Figs. 8 to 10, this form comprises a holder tube 20, operating tube 24, carrier 25 holding the stick material 30 and a hinged cap 26. The holder tube 20 comprises a body member 21 preferably of moulded material having a reduced upper end which tightly seats the metal sleeve 22. The upper end of metal sleeve 22 is provided with an annular bead 29 and the body 21 has a helical slot 23.

Cap 26 has a hinged connection 27 of the usual construction with the sleeve 22 and has a projecting tongue 28 engaging the annular bead 29 to form a snap catch. The top wall of the cap 26 is depressed or dished as indicated in Figs. 8 and 9. The operating tube 24, in the form shown, is made from flat stock rolled to form a tube and is provided with a straight slot 31, annular flange 32 and an oblique upper edge forming, in effect, projections 33. Bottom plate 34 is secured to the tube 24 by rolling or spinning over its edges onto flange 32 to form a knurled operating ring or member for operating the container.

Carrier 25 has a projection 35 engaging in slots 23 and 31 and has a plurality of nibs 36 for seating the stick material 30 as indicated.

Parts are assembled, as indicated in Fig. 8, which illustrates the fully retracted and closed position of the container with the projection 35 in the bottom of slot 31. After assembly, the oblique projections 33 are bent over the upper edge of body 21 so that the body 21 is held between these bent over projections 33 and the hand operating member 34 in such manner that a small relative longitudinal motion is possible.

To operate the container from the closed position shown in Fig. 8, the hand operating member 34 is pushed longitudinally upward to cause the oblique portions 33 to engage the cover 26. The

elasticity of the metal of bead 29 and tongue 28 causes the cover to open with a snap action taking the position somewhat as illustrated in Fig. 9. The operating member 34 is then rotated in the usual manner, causing the stick material 30 to advance the desired distance.

After use, the operating member 34 is rotated in the opposite direction to retract the stick material. The friction between the carrier member 25 and operating member 24 causes the latter to take its lowermost position as illustrated in Fig. 8 so that after the stick material is fully retracted, the cover 26, which is closed manually, may be closed without engaging the operating tube 24. It will be understood that there is enough friction between the parts to hold them together with reasonable tightness so that there is no looseness in operation.

Referring now to the third form illustrated in Figs. 11 to 17, this container comprises a holder tube 40, operating tube 41, hinged cap 42, carrier 43 holding stick material 58 and finger piece 44. The holder tube 40 comprises a body 45 of the general configuration shown in Fig. 17 having a sleeve 46 on its upper reduced end. The sleeve 46 has an annular bead 56. The body 45 has a straight internal groove 48 and a circular slot 49 having a vertical offset 50.

The cap 42 is provided with a catch tongue 55 forming a catch with the bead 56 so that when the cap is closed manually a snap engagement is obtained between tongue 55 and bead 56. The operating tube 41 which may be made from flat stock has a helical slot 52 and an oblique projection 54 and an opening 53 as illustrated in Fig. 16.

The parts are assembled as illustrated in Figs. 11 and 13, Fig. 11 representing the parts in fully retracted position, and Fig. 13 illustrating the condition of assembly before the positioning of finger piece 44 and bottom plate 61. The finger piece 44 has a pin 59 having an annular groove 60, the pin passing through slot 50 with hole 53 being seated in the groove 60. After assembly, a bottom 61 may be secured to the holder tube 40 in any desired manner.

To operate the container, the finger piece 44 is advanced longitudinally in the offset 50. This causes the oblique portion 54 to engage the cover 42 overcoming the elasticity of catch parts 55, 56, 50 causing the cover to snap open, as described above in connection with the other forms. The finger piece 44 is then moved around the circular groove 49, causing the stick material 58 to advance to the desired extent. After use, the finger piece 44 is rotated in the opposite direction to the offset 50, after which the cap 40 may be closed manually, the engagement of the cap 42 with the oblique portions 54 moving the finger piece 44 to the bottom of offset 50. If desired, finger piece 44 may be moved to the bottom of offset 50 before the cap 42 is manually closed.

It will be understood that the thick walled bodies 6, 20, and 45 may be made of attractive moulded material, or, if desired, metal, while the sleeves 1, 22 and 46 are made preferably of metal and may have sharp contrast with the material of the body to produce an attractive appearance. Furthermore, the operating tubes although illustrated as being made from flat stock, may also be made from tubular stock and the knurled operating members instead of being secured in the manner illustrated in Figs. 1 and 8 may be soldered or otherwise secured to the operating tubes.

Furtherfore, the helical slots in the forms illustrated in Figs. 1 and 8 may be placed in the operating tube and the straight slots may be placed in the outer holding tubes as suggested by Grant Patent No. 1,306,179, patented June 10, 1916.

Thus, holders for stick material have been disclosed which are rugged in construction and inexpensive to manufacture, easy to operate as well as attractive in appearance. They may be used to hold any kind of material and to dispense any kind of material, for example, lip sticks and eye brow pencils, etc.

While certain novel features of the invention have been disclosed and are pointed out in the annexed claims, it will be understood that various omissions, substitutions and changes may be made by those skilled in the art without departing from the spirit of the invention.

20 What is claimed is:

1. In a holder for stick material and the like, an outer holder tube, an inner operating tube disposed therein, a carrier member within said operating tube, said tubes having intersecting slots, said carrier member having a projection in said slots whereby relative rotation of said tubes advances said carrier member, a cover hinged to said holder tube, catch devices on said cover and holder tube, said operating tube having a cam surface, said cover having a portion engaging said cam surface whereby the initial relative rotation of said members causes said cover to snap open, said cover being closed manually, said operating tube having a lower hand-engaging base disposed against the lower end of said holder tube and an upper abutment member disposed over the upper end of said holder tube to hold said holder tube snugly therebetween.

2. In a holder for stick material and the like, an outer holder tube, an inner operating tube disposed therein, a carrier member within said operating tube, said tubes having intersecting slots, said carrier member having a projection in said slots whereby relative rotation of said tubes advances said carrier member, a cover hinged to said holder tube, catch devices on said cover and holder tube, said operating tube having a cam surface, said cover having a portion engaging said cam surface whereby the initial relative rotation of said members causes said cover to snap open.

3. In a holder for stick material and the like, an outer holder tube, an inner operating tube, said tubes having intersecting slots, a carrier member within said operating tube having a part disposed in said slots whereby relative rotation of said tubes advances said carrier member, a hand-operating part on the lower end of said operating tube and disposed below the lower end of said holder tube, a cover pivoted to said holder tube, catch devices between said cover and holder tube, said holder tube and operating tube having a limited relative longitudinal movement thereby causing said operating tube to engage said cover to snap it open, after which said hand operating part may be rotated to advance said carrier member.

4. In a holder for stick material and the like, an outer holder tube, an inner operating tube, said tubes having intersecting slots, a carrier member within said operating tube having a part disposed in said slots whereby relative rotation of said tubes advances said carrier member, a hand operating base on the lower end of said operating tube and disposed below the lower end of

said holder tube, a cover pivoted to said holder tube, catch devices between said cover and holder tube, said operating tube having a part engaging over the upper end of said holder tube, said holder tube having a limited relative longitudinal movement on said operating tube between said base and said part thereby causing said operating tube to engage said cover to snap it open, said cover being closed manually.

5. In a holder for stick material and the like, 10 a holder tube, an operating tube therein, said tubes having intersecting slots, a carrier member within said operating tube and having a part in said slots, whereby relative rotation of said tubes advances said carrier member, said holder tube 15 having a circular slot at the bottom thereof and a short vertical notch at the end of said circular slot, a finger piece disposed in said circular slot and connected to said operating tube, a cover hinged to said holder tube, catch devices on said 20 cover and holder tube, said operating tube having a limited vertical movement, when said finger piece is advanced longitudinally in said notch, to engage said cover and cause it to snap open, said finger piece then moving in said circular slot to 25 thereafter advance the carrier member, said cover being closed manually.

6. In a holder for stick material and the like, a holder tube having a longitudinal slot, an operating tube therein having a helical slot, a carrier member within said operating tube and having a part in said slots, whereby relative rotation of said tubes advances said carrier member, said holder tube having a circular slot at the bottom thereof and a short vertical notch at the end of 30 said circular slot, a finger piece disposed in said circular slot and connected to said operating tube, a cover hinged to said holder tube, catch devices on said cover and holder tube, said operating tube having a limited vertical movement, 40 when said finger piece is advanced longitudinally in said notch, to engage said cover and cause it to snap open, said finger piece then moving in said circular slot to thereafter advance the carrier member, said cover being closed manually. 45

7. In a holder for stick material and the like, a holder tube, an operating tube therein, said tubes having intersecting slots, a carrier member within said operating tube and having a part in said slots, whereby relative rotation of said tubes 50 advances said carrier member, said holder tube having an operating slot with a circular part, a finger piece disposed in said operating slot and connected to said operating tube, a cover secured to said holder tube, said operating tube 55 having a limited movement when said finger piece is advanced in said slot to engage said cover and cause it to open, said finger piece moving in said circular part to move the carrier member.

8. In a container, a holder tube, a cover, a hinge freely swiveling said cover directly to said holder tube, an operating tube within said holder tube and having a hand-engaging member at the bottom thereof, said tubes having intersecting slots, a carrier within said operating tube and 65 having a part disposed in said slots, resilient catch devices on said holder tube and cover, the upper edge of said operating tube having a cam surface directly engageable with a projection on said cover, whereby initial rotative movement of 70 said hand-engaging member to advance the carrier causes said cam surface to engage said projection to overcome said catch devices and cause the resiliency thereof to snap open the cover, said cover being closed manually. 75

9. In a container, a holder tube, a cover, a hinge freely swiveling said cover directly to said holder tube, an operating tube within said holder tube and having a hand-engaging member on the bottom thereof, said tubes having intersecting slots, a carrier within said operating tube and having a part disposed in said slots, resilient catch devices on said holder tube and cover, said carrier being fed by rotation of said hand-engaging member, said operating tube being directly engageable with said cover, whereby movement of said hand-engaging member overcomes said catch devices and causes the resiliency thereof to snap open the cover, said cover being closed manually.
10. In a container, a holder tube, a cover, a

hinge freely swiveling said cover directly to said holder tube, an operating tube within said holder tube and having a hand-engaging member on the bottom thereof, said tubes having intersecting slots, a carrier within said operating tube and having a part disposed in said slots, resilient catch devices on said holder tube and cover, said operating tube directly engaging said cover, whereby initial rotative movement of said hand-engaging member to advance the carrier causes said operating tube to engage said cover to said catch devices and cause the resiliency thereof to snap open the cover, said cover being closed manually.

CHARLES N. CORYELL.
